Warren E. Willis
ATTORNEY

UNITED STATES PATENT OFFICE

SAMUEL ALEXANDER, OF NEW YORK, N. Y.

KNIFE AND GUARD HANDLE

Application filed December 6, 1929. Serial No. 412,103.

This invention relates to cutlery and more specifically to knives as combined with holders or handles in which the blade may be folded as a scabbard or sheath when not required for use.

Such knives are for the use of workmen and artizans, being of wide application for miscellaneous purposes, possessing unusual strength and cutting qualities, and, as the blade is completely protected when retracted, are safely handled in transit.

A further feature of the invention is in the provision of a handle affording an unusually secure grip by which the blade is maneuvered during operation.

These and other advantageous features, such as simplicity, moderate cost of construction and ease of operation, are accomplished by the novel construction, combination and arrangement of parts hereinafter described and illustrated in the accompanying drawings constituting an essential portion of this disclosure, and in which:

Figure 1 is a perspective view of an embodiment of the invention, showing the manner in which it is operated.

Figure 2 is a plan view of the same with the blade in extended, operative position.

Figure 3 is an edge view thereof.

Figure 4 is a similar view of the device showing the blade in a folded or retracted position.

Figure 5 is an enlarged fragmentary sectional view of a part of the handle.

The blade 10 is generally triangular in shape, having opposed angular cutting edges 11, an essentially rectangular back 12 and a blunt point 13 at the front, the blade being flat throughout.

The back 12 is provided with two spaced openings 14 receptive of screws 15 having broad low heads 16 which may be slotted to receive the tang of a screw driver or similar turning element.

These screws are also passed through registering openings 17 in a plate 18 and are equipped with nuts 19 preferably adapted for hand operation.

The plate 18 extends along one side of the knife back to project slightly beyond its end

edges and is curled to produce an essentially cylindrical handle 20, slightly resilient to the grasp of an operator's hand, some of the fingers of which enter an elongated transverse opening 21 disposed between the handle and blade back. 55

The edges 22 of the opening are rolled tightly upon the plate thus providing a smooth internal border or frame incapable of cutting or injuring the fingers in the opening, while the digit finger is extended to guide the implement as seen in Figure 1.

When the knife is not in use one of the screws may be removed and the other slackened to permit the blade 10 to be rotated on the slackened screw as a pivot, the blade swinging over the level surface of the plate 18, through an opening 23 into the handle space 24, as seen in Figure 4, in which position the cutting edges are protected from injury by accidental contact with other articles and at the same time damage to adjacent objects is prevented. 70

From the foregoing it will be seen that a double edged blade has been disclosed, easily sharpened or removed entirely from its handle for grinding or like purposes. 75

It is equally obvious that the protection afforded the blade by its scabbard-like handle is efficient, and due to the grip obtainable by the handle, when the blade is extended, the cutting edges may be firmly pressed against the work part and guided with entire accuracy. 80

Obviously the cutting of cords; shaping of suitable material in the manner of a drawknife, applying putty and other manifold purposes are effectively accomplished. 85

From the foregoing it will be seen that a simple device for this purpose has been disclosed in the preferred form of its embodiment, but it is not desired to restrict the details to the exact instruction shown, it being obvious that changes, not involving the exercise of invention, may be made without conflicting with the scope of the appended claims. 90

Having thus described the invention, what is claimed as new and desired to secure by Letters Patent, is:—

1. A knife comprising a flat triangular

blade having two cutting edges, a rectangular plate provided with a finger receiving opening, an open cylindrical handle integral with said plate, and means for clamping 5 said blade to said plate, one of said clamping means being removable and the other to act as a pivot on which said blade may turn to seat entirely on the plate and enter the space in said handle, both of said cutting 10 edges being guarded thereby.

2. A knife comprising a flat triangular blade having opposed cutting edges at the front, and provided with a pair of spaced openings in its rear portion, a rectangular 15 sheet metal plate having registering openings, manually operable bolts passing through the openings, either of said bolts being removable and adapted to act as pivots, and a resilient hollow cylindrical handle formed on 20 the outer edge of said plate, the free edge of said handle being spaced above the plate to receive said blade therebelow when turned upon one of the pivot bolts.

3. A knife comprising a flat triangular 25 blade having two proximate cutting edges and a plain edge opposed thereto and provided with a pair of spaced openings in its rear portion, a rectangular sheet metal plate having registering openings near one of its edges, 30 manually operable bolts passing through the openings in said blade and plate, either of said bolts acting selectively as a pivot on which the blade and plate may relatively rotate, a coiled cylindrical grip handle on the 35 opposite edge of said plate, said handle having an open longitudinal space in the plane of said blade into which the blade may be swung on either of its pivot bolts, and an elongated rectangular opening in said plate intersecting 40 jacent and parallel said handle and blade having beaded edges.

4. A knife comprising a flat triangular blade having two angularly disposed convergent cutting edges, and a plain rear edge 45 opposed thereto, a handle, a pair of pivot bolts to clamp said blade to one side of said blade, and means on said handle to act as a guard for both cutting edges coincidentally when swung thereunder, on either pivot bolt 50 selectively, said bolts constituting removable means for preventing the return of the blade to its operative position when one of the cutting edges is positioned within said handle.

In testimony whereof I affix my signature.
55 SAMUEL ALEXANDER.
